UNITED STATES PATENT OFFICE.

ELLA M. ADAMS, OF OAKLAND, CALIFORNIA.

HAIR-WAVING DEVICE.

Application filed February 10, 1925. Serial No. 8,157.

My invention has for its object means for marcelling or curling hair and belongs to that class of devices wherein portions of hair are curled about a plurality of tubular members each of which is provided with a part or parts which grip and hold in place a portion of hair, and thereafter a heated rod is inserted in the tube which thereupon becomes hot, and by conduction subjects the hair coiled thereon to the necessary degree of heat to establish a lasting curl when the device is removed.

Another object is a device of the character described wherein a funnel shaped inlet is clipped over the tubular member to facilitate the insertion of the heated rod, without coming in contact with the hair or scalp of the operator.

Other objects will appear from the drawings and specifications which follow:—

Fig. 1 illustrates a part of the tubular member and hair clamping means in extended or outfolded position.

Fig. 2 indicates the device of Fig. 1 folded in position and with the heating rod partly inserted therein.

Fig. 3 shows the device as applied and with a portion of hair wrapped around the tubular member and clamped in position and with the funnel member to facilitate the insertion of the rod shown dotted in position of use.

Fig. 4 is a detail of the funnel member.

Fig. 5 is a detail of the heating rod.

My invention is particularly directed to the funnel member one form of which is illustrated in Fig. 4 and which is shown by dotted lines in position on the curling device in Fig. 3 in combination with the other conventional parts.

The numeral 1 indicates a tubular member through which pivots a loop of spring wire consisting of the legs 2, 3. A keeper 4 is provided which is slidable on said legs and engages over the tubular member as shown in Figs 2 and 3 when the loop is clamped about the hair.

At 5 is a short projecting end of spring wire adapted to engage the shorter hairs, as well known.

6 indicates a metallic rod adapted to be heated and inserted into the tubular member 1, and this rod is preferably provided with a heat insulated end 7.

My funnel member comprises a pair of bent side plates 8, 9, pivoted together at 10,

11 and normally held in the position shown in the Figure by the coil spring 12.

The projecting ends of these plates are adapted to be gripped with the fingers and when compressed pivot about 10 and 11 overcoming the spring resistance and opening the lower, or end portions 13, 14 to admit of being clamped over the end of the curling device as shown in Fig. 3. When the fingers are released the spring grips the sides 13, 14 about the end of the tubular or curling member and the flaring ends 8, 9 provide a funnel entrance for the rod 6.

The device is used as follows:

The curling member is first outfolded as shown in Fig. 1 and the hair wrapped about the tubular member 1, with the shorter hairs engaged under the wire 5. The loop 2, 3 is then hinged over the wrapped hair and the keeper 4 slid down over the end of the tube 1. The parts will then present the full line appearance of Fig. 3.

A plurality of these curling devices are distributed over the head, curling such portions of the hair as desired and the operator then grips the end plates 8, 9 of my funnel member and engages this over one of the curling members in place and as shown by the dotted line in Figure 3. The rod 6 is then heated and inserted into the tubular member 1, my funnel member aiding in locating the tube entrance and providing a sufficient clearance space for the passage of the rod 6 and the head 7, and enabling the operator to avoid burning the hair or scalp.

The funnel member is then removed by again gripping the side plates 8, 9 as before, leaving the heated rod in the tube and the funnel member is then applied to a second curling device and the above described procedure is repeated for each of the curling devices employed.

Particular attention is directed to the spring wire member 5 which is wrapped about the tube 1, one end engaging over the end of the tube and the other end 15 lying against the tube and forming a spring member under which the shorter hairs are held during operation.

I claim:—

1. A device for curling hair comprising a tubular member and means for gripping hair curled about said member, a funnel shaped device adapted to clamp on the end of said tubular member and to direct an implement into said tube comprising a pair

- of covered sides pivoted together and spring means therebetween adapted to force the small end of said sides together and to force the larger ends of said sides apart.
- 5 2. A device for curling hair consisting of a funnel shaped member and gripping means associated therewith adapted to grip about the end of a tubular element and comprising a pair of curved sides pivoted together and spring means therebetween adapted to force the small ends of said sides together and to force the larger ends of said sides apart.
- 10

3. A device as set forth in claim 1 wherein there is a spring wire wrapped about said tubular member having one end engaging over the end of said member and the other end lying parallel with and against said tubular member.

4. A device as set forth in claim 2 wherein there is a spring wire wrapped about said tubular member having one end engaging over the end of said member and the other end lying parallel with and against said tubular member.

ELLA M. ADAMS.
